REFRIGERATING CABINET

John Edward Gloekler, Pittsburgh, Pa.

Application July 12, 1932, Serial No. 622,086

10 Claims. (Cl. 62—89.5)

My invention relates to improvements in refrigerating cabinets for preserving and exhibiting perishable articles, as meats, dairy products, or the like.

5 It has for its object to provide in such a cabinet a main containing chamber in which the supporting trays are arranged above a part level and part inclined bottom floor to the best advantage for exposure to view through a front inclined window. The invention also includes 10 means for illuminating the interior with most advantageous distribution of the light; means providing circulation of incoming and refrigerating air; a rear access door; and other features 15 of construction and advantage.

Also to provide in a double chamber cabinet, a lower compartment with an intervening separating floor or partition sloping upwardly at the back in the same general direction as the upper 20 supporting tray, and also providing a corresponding increase in the height of the lower chamber adjacent its rear doors, as shall be more fully hereinafter described.

Referring to the drawings:

25 Fig. 1 is a perspective view of the entire cabinet from the front;

Fig. 2 is an enlarged vertical sectional view on the line II—II of Fig. 1.

The refrigerating cabinet illustrated herein is 30 constructed in the same general manner as cabinets of standard construction. It provides a main food or other article containing chamber A enclosed within a double glass front wall 2, a rear wall having sliding doors 3, a flat top 4, 35 and a bottom wall or floor consisting of a front horizontal section 5, and a rear inclined section 6.

Floor 5—6 may be mounted directly above any 40 suitable supporting base or supporting legs, or, as shown, above an enclosed supplemental refrigerating chamber B, incorporated with the general framework, as hereinafter described.

It will be understood that the invention is not limited to the particular form of cabinet as to being single or double, and may be varied in construction from the design shown, or may be incorporated in a single or double chamber installation.

The condiments, food, or other articles to be 50 contained in chamber A are supported by a lower series of pans or other convenient vessels 7 on the lower brackets 8, of wire-work or other suitable construction, resting on the horizontal bottom 5 longitudinally at the front lowermost portion of the chamber.

55 A series of secondary pans 9 of the same gen-

eral kind extend longitudinally at a higher level, and are supported upon similar brackets or frames 10 carried by front legs 11 resting on the rear portion of floor 5 and by supporting brackets 12 of suitable construction, on which rest the 60 upper edge portions of the pan-supporting frames.

As shown, frames 10 slope upwardly and backwardly at a higher position than the lower pans 7, the upper pans being also slightly tilted as 65 shown so as to dispose their contents in convenient range of visibility through the front windows 2. Access to either series of pans is had by opening one or more of the sliding doors 3 at the rear of the cabinet, which is also provided with a 70 rearwardly extending shelf 13 extending backwardly from the rear wall 14.

The front observation windows 2 are framed at their lower sides into the front wall or base 15 and at their upper edges into a supplemental 75 framing strip 16. Between such strip and the top 4 is provided a longitudinal cavity 17 for a series of lighting bulbs 18. These are mounted in suitable sockets secured to either side of the cavity, against strip 16 or the edge of top 4, as at 80 19, whereby to maintain the lamp sockets in suitable position for reception of the bulbs.

The inner side of the cavity is closed by one or more light panes 20 of glass through which the transmitted and reflected light issues inwardly to the interior A. The glass panes are mounted in a surrounding removable frame for separation when desired. A reflector 21 of suitable parabolic cross section is inserted above the series of lamps, whereby to reflect the light rays inwardly and downwardly at varying angles throughout the entire interior, providing for ample and economical illumination.

Outwardly beyond cavity 17 is a longitudinal ornamental coping 22 of rib construction, in 95 alternating or zigzag formation, providing an ornamental finish and having at suitable intervals outlet openings 23 for escape of heated air. Coping 22 is also removably mounted for access to the interior lamp cavity.

A refrigerating coil 24 of any suitable construction having a drip pan 24a is suspended upwardly underneath top 4 and a longitudinal downwardly extending baffle 25 is inserted slightly below the top, at one side of the coil and 105 adjacent to the upper portion of the window openings of slides 3. Baffle 25 is spaced away from the angle portion of the top and extends below the window opening so that upon opening either of the sliding doors 3, comparatively warm 110

- air from the exterior will pass inwardly and upwardly around the baffle 25 to the interior and also in contact with refrigerating coils 24, and then downwardly into and through the interior of chamber A. 5
- Likewise a similar refrigerating coil 26 is located along the lower rear portion of chamber A below the inclined pan-supports 10 as indicated, whereby to maintain the temperature of the chamber at the desired degree throughout its lower food-containing portion. 10
- Chamber B, when present, as in the double chamber construction shown, is enclosed within front wall 15a and base 27 and rear door 28. By 15 reason of the upwardly sloping floor extension 6 the height of the lower chamber is increased at the back, giving greater space for access to the interior when door 28 is opened.
- One or more trays 29 are supported within the 20 interior of the chamber, which is also provided with suitable refrigerating coils 30 having a drip pan 30a for maintaining the desired temperature, as in upper chamber A.
- The refrigerating cabinet as a whole is 25 comparatively simple in construction and economical of space, with especial advantages in showing and illuminating the contents of the upper chamber, and maintaining the temperature with relation to the contents.
- I claim: 30
1. In a refrigerating cabinet having a sloping front window, a rear opening and closing door, a top, and a floor; an illuminating casing forming a corner connection between the front window and the top having an outer perforated cover and an inner transparent wall, a lamp therein, and a reflector directing light rays towards the interior of the cabinet. 35
  2. In a refrigerating cabinet having a sloping front window, a rear opening and closing door, a top, and a floor; an illuminating casing forming a corner connection between the front window and the top having an outer transversely corrugated perforated outer cover and an inner transparent wall extending longitudinally of the cabinet, a series of lamp sockets and lamps between the cover and said wall, and a reflector located outwardly around the lamps directing light rays to the interior. 40
  3. In a refrigerating cabinet having a sloping front window, a rear oppositely sloping door, a covering top; a source of light between the top and the front window having a downwardly directing reflector, a perforated cover beyond the reflector connecting the front window and top, and a floor having a front level portion and an upwardly inclined rear portion. 45
  4. In a refrigerating cabinet having a sloping front window, a rear oppositely sloping door, a covering top; a source of light between the top and the front window having a downwardly directing reflector, a perforated cover beyond the reflector connecting the front window and top, and a floor having a front level portion and an upwardly inclined rear portion each provided with tray supporting frames at varying levels. 50
  5. In a refrigerating cabinet having a sloping front window, a rear oppositely sloping door, a covering top; a source of light between the top and the front window having a downwardly directing reflector, a perforated cover beyond the reflector connecting the front window and top, a floor having a front level portion and an up- 55
  - wardly inclined rear portion, a lowermost receptacle support on the front level portion, and an uppermost rearwardly inclined receptacle support spaced above the inclined rear portion of the floor. 60
  6. A refrigerating cabinet having a sloping front window, a rear oppositely sloping door, a connecting top, a source of light between the top and the front window having a downwardly directing reflector, a floor having a front level portion and an upwardly inclined rear portion, a lowermost receptacle support on the front level portion, an uppermost rearwardly inclined receptacle support spaced above the inclined rear portion of the floor, and a refrigerating coil located between the sloping floor portion and the uppermost receptacle support. 65
  7. In a refrigerating cabinet, a casing having a base, a vertical front wall, a vertical rear door, a transverse partition having a front level portion and a rear upwardly and backwardly inclined portion forming an upper closure for a lower refrigerating chamber, an upper sloping front window extending backwardly above the front level partition, a rear upper wall having an opening and closing door, and a covering top connecting the rear upper wall and the upper portion of the front window and spaced therefrom providing a light cavity, and a lamp therein provided with a reflector directing rays towards the transverse partition. 70
  8. In a refrigerating cabinet, a casing having a base, a vertical front wall, a vertical rear door, a transverse partition having a front level portion and a rear upwardly and backwardly inclined portion forming an upper closure for a lower refrigerating chamber, an upper sloping front window extending backwardly above the front level partition, a rear upper wall having an opening and closing door, a covering top connecting the rear upper wall and the upper portion of the front window and spaced therefrom providing a light cavity, a lamp and reflector therein, and horizontal and inclined receptacle supports located at varying levels above the level and inclined portions of the transverse partition. 75
  9. In a refrigerating cabinet, a casing having a base, a vertical front wall, a vertical rear door, a transverse partition having a front level portion and a rear upwardly and backwardly inclined portion forming an upper closure for a lower refrigerating chamber, an upper sloping front window extending backwardly above the front level partition, a rear upper wall having an opening and closing door, a covering top connecting the rear upper wall and the upper portion of the front window, horizontal and inclined receptacle supports located at varying levels above the level and inclined portions of the transverse partition, and a source of light located between the covering top and the upper portion of the front inclined window having a reflector directing light rays towards said receptacles. 80
  10. A refrigerating cabinet as in claim 8 characterized by the presence of a refrigerating coil suspended below the top and an air directing baffle therefor located between the coil and the rear wall door opening and projecting below said opening. 85

JOHN EDWARD GLOEKLER.
